ILLUMINATED MEDICINE CABINET

Edward Hulyk and Oscar R. Achabal, Cincinnati, Ohio, assignors to The F. H. Lawson Company, Cincinnati,
Ohio, a corporation of Ohio

Filed Sept. 22, 1961, Ser. No. 66,814

Term of patent 14 years

(Cl. D4—3)

Fig.1

We claim:

The ornamental design for an illuminated medicine cabinet, as shown.
